U.S. Appl. No. 29/377,626, "Building Exterior", filed Oct. 22, 2010.

* cited by examiner

Primary Examiner — T. Chase Nelson*Assistant Examiner* — Eric Goodman(74) *Attorney, Agent, or Firm* — Sterne, Kessler, Goldstein & Fox PLLC(57) **CLAIM**

The ornamental design for a building, as shown and described.

DESCRIPTION

FIG. 1 is a front perspective view of a building showing our new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken lines in the figures show portions of the building which form no part of the claimed design.
